ATTORNEY

UNITED STATES PATENT OFFICE.

GUSTAV W. MACKO, OF CHICAGO, ILLINOIS.

MECHANICAL TOY.

SPECIFICATION forming part of Letters Patent No. 733,409, dated July 14, 1903.

Application filed November 14, 1902. Serial No. 131,366. (No model.)

To all whom it may concern:

Be it known that I, GUSTAV W. MACKO, a citizen of the United States, residing at Chicago, in the county of Cook and State of Illinois, have invented a certain new and useful Improvement in Mechanical Toys, (Case No. 1,) of which the following is a full, clear, concise, and exact description, reference being had to the accompanying drawings, forming 10 a part of this specification.

My invention relates to mechanical toys, and particularly to a class of toys in which it is intended to illustrate in pantomime the movements of human figures.

15 A preferred embodiment of my invention consists in the provision of a pair of figures mounted upon a suitable base, each of which is jointed at the waist. Means are provided whereby the figures may be operated to address each other, as in the act of salutation or greeting.

A preferred embodiment of my invention is illustrated in the accompanying drawings, where I have shown a base portion 1, upon 25 which are mounted the figures A and B, the first of which is shown suitably attired. The other is disrobed to illustrate the mechanical features employed in the operation thereof. Each figure is provided with a pair of legs 2 30 and a part 3, forming the bust or trunk of the figure. To each of the said bust portions is attached a head 4, which may be provided with a hat 5. The arms 6 6 may be pivotally attached to the bust portion 3, as shown. 35 The legs and the trunk portion 3 are desirably connected by a flat spring 7. However, it will be apparent that a helical coiled spring might advantageously be employed for this purpose. An actuating-string 8 is run through 40 the base 1 and up the front of the figure, where it is attached to the front of the trunk portion 3, as shown. By exerting a downward pull upon the string 8 the trunk portion 3 and the head and arms connected therewith are 45 moved forward and downward, as in the act of bowing. By a suitable manipulation of the strings connected with the figures they

may be made to salute each other and to simulate various antics calculated to amuse and entertain.

It is immaterial to the spirit of my invention in what way the figures are attired or what characters they are intended to represent. A desirable embodiment of my invention, however, contemplates the provision of 55 figures intended to represent "Alphonse and Gaston," as frequently illustrated in comic newspapers supplements. Other means might desirably be employed for the purpose of causing the actuation of the figures, and while 60 I have shown one preferred embodiment of my invention many modifications thereof which come within the spirit of my invention will be apparent to those skilled in the art. I do not, therefore, wish to be limited to the 65 precise disclosure herein described; but,

Having described my invention, I claim as new and desire to secure by Letters Patent—

In a mechanical toy, the combination with a mounting-block 1, of mechanical figures 70 dressed as human beings mounted at either end thereof and facing each other, each of said figures consisting of a leg portion 2 rigidly secured to said mounting-block 1, a body portion 3 having a head 4, a flexible leaf-spring 7 interposed between said body and said leg portion, and a string secured to the front of said body portion and passing downwardly alongside of the leg portion through an opening in said mounting-block, a pull 80 upon said string causing the body portion of said figure to move forward and downward as if bowing to the figure disposed at the other end of said mounting-block, a release of said string allowing said body portion to 85 return to its normal position, substantially as described.

In witness whereof I hereunto subscribe my name this 6th day of November, A. D. 1902.

GUSTAV W. MACKO.
